MULTIPOLE CIRCUIT BREAKER

John G. Jackson, Detroit, Mich., assignor to
 Square D Company, Detroit, Mich., a corpora-
 tion of Michigan

Application February 28, 1951, Serial No. 213,166

10 Claims. (Cl. 200—88)

1

This invention relates to electric circuit breakers automatically operable in response to current overload and more particularly to automatic electric circuit breakers of the multipole type.

The object of this invention is to provide an improved multipole circuit breaker mechanism in which all poles will be released in response to an overload in any one pole in the circuit breaker.

Another object of the invention is to provide a multipole circuit breaker mechanism in which the switching means for individual poles are independently latched and in which current responsive release of one switching means will cause release of the other switching means in response to movement of the one switching means.

Another object of the invention is to provide a multipole circuit breaker mechanism in which the switching means for individual poles are independently latched and in which there is a common means for engaging and releasing said latching means and interengaging means on each of said switching means and common means so that upon current responsive release of one of said switching means it will move to engage said common means and effect movement thereof to unlatch all of said switching means.

Another object of the invention is to provide a multipole circuit breaker mechanism in accordance with the preceding object in which the common means is magnetically attracted upon heavy overload to effect substantially simultaneous release of all the switching means.

Other objects and features of the invention will be readily apparent to those skilled in the art from the specification and appended drawings illustrating certain preferred embodiments in which:

Figure 1 is a vertical sectional view of the circuit breaker according to the present invention.

Figure 2 is a transverse sectional view along line II—II of Figure 1.

Figure 3 is an exploded perspective view of the common trip mechanism.

The circuit breaker illustrated in the drawings as one form of the present invention includes a generally cup-shaped insulating base 1 having a generally centrally disposed dividing wall 2 serving to insulate the breaker poles from each other. Within each of the compartments formed by the central wall 2 and the side walls of the base 1 is mounted a circuit breaker pole mechanism, the separate poles having certain duplicate parts which will now be described.

Each of the poles includes a stationary contact 3 mounted on a connector 4 which is supported on an end ledge 5 of the circuit breaker exterior

2

by a spun-over portion of a threaded metallic insert 6 which receives a terminal screw 7. The chamber about the stationary contact 3 is lined with insulating sheets 8 of fiber or other material and within this chamber is a movable contact 11 carried upon the end of a rigid switching contact bar 12. The top edge of the contact bar 12 is provided with a slot at 13 which receives the inner end of a slot within the longer leg of a U-shaped member 14 to form a pivotal mounting for the contact bar 12. The member 14 is guided for rectilinear movement at right angles to the back of the base by means of formations within the base.

15 A connector 15 is mounted upon an end ledge 16 at the opposite end of the breaker by a spun-over portion of a metallic insert 17. The interior end of the connector 15 has a central pressed in arm 18 upon which is rigidly secured a bimetallic member 19. Adjustable means indicated generally at 21 is provided for adjusting the calibration of the breaker by moving the arm 18.

20 Fixed to the bimetallic member 19 by means of a rivet 10 near its midpoint is a resilient spring

25 strip 22 formed to provide a latching tip at 23 on a lower leg 25 which is biased by its resiliency away from the plane of the bimetallic member 19, but whose position is limited by the engagement with the back of the bimetal of the flange 30 24 formed at the end of the leg 25. The other leg 26 of the spring strip 22 is formed as shown to extend toward the front of the breaker to bias a rotatable insulating supporting shaft 27 in a counter-clockwise direction, as viewed in Figure

35 1. On the side of the bimetallic member 19 opposite the resilient strip 22 is a magnetic yoke 28 of generally U-shape with its legs on opposite sides of the bimetallic member. The yoke 28 is also mounted by the rivet 10.

40 A flexible lead 31 interconnects the free end of the bimetallic member 19 and the contact bar 12, and the end of the contact bar 12 remote from the contact 11 is latched in operating position by means of the latching tip 23 on the leg

45 25 of the resilient spring member 22. A compression spring 32 provides a bias for holding the contact 11 against the stationary contact 3 when the breaker is closed and biases the contact 12 for rotation about the pivotal engagement of the 50 notch 13 with the member 14 when the breaker is tripped, such rotation being prevented by engagement of latching tip 23 with the end of bar 12.

Upon a shaft 34 is pivotally mounted an operating handle 35 having an interior cam surface which includes a flat stable manual "Off" portion 36 and a resetting tip 37. To close off the top of the circuit breaker, there are provided common cover plates 38 and 39 sealably attached to the base as by spun-over portions

of metallic rivets (not shown). A light spring 41 is provided to operate on the handle 35 to provide a definite position "On" therefor.

The single pole mechanism heretofore described is duplicated for each pole desired in the breaker which are here illustrated as two. To form these single poles into a multipole circuit breaker, there is provided a common trip mechanism which is illustrated in perspective in Figure 3 and which comprises a pair of magnetizable armature members 42 and 43 slotted at 44 and 45 as shown in Figures 2 and 3 to permit movement of the ends of contact bars 12 therethrough. The armature members 42 and 43 are rigidly mounted within the insulating shaft 21 so that the armature members and shaft rotate as a unit. Upon the armature members 42 and 43, adjacent slots 44 and 45, are mounted cams 46 engageable by pins 47 mounted one each adjacent the latching ends of the contact bars 12. The armature members 42 and 43 are positioned opposite the legs of the yoke 28 so as to be attracted thereto upon energization of the yoke in response to the passage of heavy overload currents through the bimetallic member 19 which in effect forms a single turn about the magnetic circuit. The armature members 42 and 43 are also positioned so that as they rotate in a clockwise direction, as viewed in Figure 1, they will engage their respective latching tips 23 to move them into unlatching position. It is apparent that the width of latching tips 23 is greater than the width of the adjacent portions of slots 44 and 45, as shown in Figure 3, so that armatures 42 and 43 may engage their respective latching tips. The exterior portions of the operating handle 35 are rigidly connected together by means of a U-shaped metallic member 48 which joins the handles together for common movement as a unit.

The operation of the circuit breaker will now be described. The parts are shown in Figure 1 with the breaker in the open position. Rotation of the handle 35 in a counterclockwise direction as viewed in Figure 1 will allow the U-shaped member 14 to move forwardly under the bias of spring 32 to rotate contact bar 12 about its pivotal engagement with the latching tip 23 of the resilient spring strip 22 to move the movable contact 11 into engaged position with the stationary contact 3, placing the breaker in the "On" position. To again place the parts in manual open circuit position, the handle is rotated in a clockwise direction from its "On" position to the "Off" position of Figure 1.

Upon an occurrence of a sustained moderate overload through any one of the circuit breaker poles, the bimetallic member 19 for that pole will become heated and will flex to move in a clockwise direction to move the spring 22 mounted thereon bodily toward the left as viewed in Figure 1, thus moving its latching tip 23 to a position to release the end of the cooperating contact bar 12 which then rotates in a clockwise direction under the bias of compression spring 32 about its pivotal engagement with the longer leg of the U-shaped member 14. This movement of the contact bar 12 forces its pin 47 against its associated cam 46 and thereby rotates the armature members 42 and 43 and shaft 21 about their pivotal mounting in a clockwise direction as viewed in Figure 1. As the armatures 42 and 43 are moved toward their respective yoke members 28, the one associated with the unreleased pole will engage the latching

tip 23 for that pole and will move it toward its supporting bimetal member against the bias of strip 22 into unlatching position to thus release all contact bars 12 upon thermal current responsive release of any one of them.

A further feature of this invention is apparent upon the occurrence of a heavy overload and short circuit currents through one or more of the breaker poles. Upon such an occurrence, the 10 magnetic attraction between the yoke 28 and the armatures becomes sufficient to rotate the armatures bodily in a clockwise direction until they engage the latching tips 23 and move them toward their supporting bimetallic members and into unlatching position. As the armatures are 15 rigidly connected together, they will effect substantially simultaneous release of all of the contact bars upon the attraction of any of the armatures caused by heavy overload or short circuit currents in the pole with which it is associated.

After an automatic opening of the circuit breaker, it may be reset by rotating handle 35 into its extreme clockwise position in which the reset tip 37 forces the U-shaped member to its 20 rearward position in which the contact carrying end of the contact bar 12 engages the base and causes the contact bar to rotate in a counterclockwise direction as the member 14 is forced rearwardly until the latching end of the contact bar passes below the latching tip 23. Release of 25 the handle 35 will permit the parts to return to the position of Figure 1 under the bias of spring 32 with the end of the contact bar engaging the latching tip 23 and with the movable contact 11 in the "Off" position.

While this invention has been described in connection with a particular circuit breaker mechanism to show a complete operative structure, it is understood that the tripping means 30 according to the present invention is not limited to any particular mechanism but may be utilized in many other distinct mechanism forms to which it is adapted and, while certain preferred embodiments of the invention have been specifically disclosed, it is understood that the invention is not limited thereto, as many variations will be readily apparent to those skilled in the art and the invention is to be given its broadest possible interpretation within the terms of the following 35 claims.

What is claimed is:

1. In a multipole automatic electric circuit breaker, a plurality of pairs of separable contacts and elements individual to each pair releasable to effect separation of the corresponding pair of contacts, means mounting one of each pair of contacts upon the element associated with that pair of contacts, independently operable latching means for each of said plurality of elements, current responsive tripping means for effecting unlatching of the latching means including both thermal and magnetic tripping means individual to each element of said breaker and energized in response to current flow through the pair of contacts controlled by their associated element, means mounting said individual magnetic tripping means for common movement as a unit to cause unlatching of the latching means for all elements due to a current overload through any 40 pair of contacts, said individual thermal tripping means effecting unlatching of the latching means of their associated individual element due to a current overload through the associated pair of contacts, and means on each of said elements engageable with said magnetic means to effect

unlatching movement of all said latching means in response to release of any element.

2. In a multipole automatic electric circuit breaker, a plurality of pairs of separable contacts and elements individual to each pair releasable to effect separation of the corresponding pair of contacts, means mounting one of each pair of contacts upon the element associated with that pair of contacts, independently operable latching means for each of said plurality of elements, a bimetallic member in series circuit with each pair of contacts, each latching means being movable by its associated bimetallic member in response to overload current therethrough to release its associated element, magnetic means common to all pairs of contacts and energized in response to overload current through any pair to move all of said latching means to unlatching position, and means on each element engageable with said magnetic means when an element is released by movement of a bimetallic member to effect unlatching movement of all the latching means.

3. In a multipole automatic electric circuit breaker, a plurality of pairs of separable contacts and elements individual to each pair releasable to effect separation of the corresponding pair of contacts, independently operable latching means for each of said plurality of elements, a bimetallic member in series circuit with each pair of contacts, said latching means including resilient strips mounted on said bimetallic members and movable therewith and relative thereto, a magnetic circuit for each pair of contacts energized by current flow therethrough and each including an armature attracted on overload through its associated pair of contacts to move the associated latching means into unlatching position, said armatures being rigidly connected for common movement as a unit, a pin mounted on each of said elements and adjacent to the latched end of each of said elements, a cam surface on each of said armatures, said pins engaging said cam surfaces after bimetal release of said elements to move said armatures and latching means and release all the elements in response to overload current through any pair of contacts.

4. In a multipole automatic electric circuit breaker, a plurality of pairs of separable contacts and elements individual to each pair releasable to effect separation of the corresponding pair of contacts, means mounting one of each pair of contacts upon the element associated with that pair of contacts, independently operable latching means for each of said plurality of elements, current responsive tripping means for effecting unlatching of the latching means, means common to all elements of said circuit breaker operable to move said latching means to unlatched position, and surfaces on said elements engageable with said common means to effect unlatching movement of all the latching means in response to an overload in any one or more pairs of contacts.

5. In a multipole automatic electric circuit breaker, a plurality of pairs of separable contacts and elements individual to each pair releasable to effect separation of the corresponding pair of contacts, means mounting one of each pair of contacts upon the element associated with that pair of contacts, independently operable latching means for each of said plurality of elements, current responsive tripping means for effecting unlatching of the latching means, means common to all elements of said circuit breaker and

operable to move said latching means to unlatched position, abutments on each of said elements adjacent the latched ends of said elements, cam surfaces on said common means, said abutment engaging said cam surface after release by said current responsive tripping means to move said common means and the latching means to release all the elements in response to overload current through any pair of contacts.

10 6. In a multipole automatic electric circuit breaker, a plurality of pairs of separable contacts and elements individual to each pair releasable to effect separation of the corresponding pair of contacts, means mounting one of each pair of contacts upon the element associated with that pair of contacts, independently operable latching means for each of said plurality of elements, a bimetallic member in series circuit with each pair of contacts, said latching means including resilient strips mounted on said bimetallic members and movable therewith and relative thereto, means common to all elements of said circuit breaker and operable to move said latching means relative to said bimetallic members to unlatched position, and abutments on said elements engageable with said common means to effect unlatching movement of all latching means in response to an overload in any one or more pairs of contacts.

15 7. In a multipole automatic circuit breaker, a plurality of pairs of separable contacts, an element individual to each of said pairs for carrying one of the associated pair of contacts, means biasing said elements for movement, independently operable latching means for each of said elements, said elements being releasable to effect separation of the corresponding pair of contacts, current responsive tripping means for effecting unlatching of each of said latching means including thermal and magnetic means, each of said last mentioned means being energized in response to current flow through the element with which it is associated, said magnetic tripping means being operatively common to all poles of the breaker and causing unlatching of the latching means for all other poles in response to operation of the latching means in one pole by said thermal means.

20 8. The device as defined in claim 7 in which said elements carry abutments for operating the magnetic means upon release of the elements by said thermal means.

25 9. The device as defined in claim 7 so constructed and arranged that all magnetic means are simultaneously operated to effect release of all latching means upon the occurrence of high current overloads in one or all poles.

30 10. The device as defined in claim 8 in which said magnetic means carry cam surfaces engageable by said abutments upon release of said elements by said thermal means.

JOHN G. JACKSON.
